UNITED STATES PATENT OFFICE.

ANGELO PROFETO AND HARRY E. GROSS, OF PITTSBURGH, PENNSYLVANIA.

BEDSTEAD.

1,108,620.

Specification of Letters Patent. Patented Aug. 25, 1914.

Application filed April 8, 1913. Serial No. 759,677.

To all whom it may concern:

Be it known that we, ANGELO PROFETO, a subject of the King of Italy, and HARRY E. Gross, a citizen of the United States, residing at Pittsburgh, in the county of Allegheny and State of Pennsylvania, have invented certain new and useful Improvements in Bedsteads, of which the following is a specification.

Our invention relates to the class of supports for bedsteads and it has for its object to provide, in connection with the supporting frame of the bed springs, means whereby the supporting frame may be mounted upon a metal bedstead framework having main side and end bars, or upon the slats of an ordinary wooden or other bedstead.

The particular improvement consists in a novel construction of support, hanger or clevis, pivotally connected with the cross bar members of the supporting frame, in such a manner as to be thrown out underneath the endmost member of the frame and to engage the side bars of the main bedstead frame, or to be thrown backwardly alongside with the member to which it is pivoted with sufficient resilient binding engagement to fixedly hold it in retracted position and away from interference with the slats or other portions of the bedstead frame.

The invention is illustrated in the accompanying drawings in which—

Figure 1 is a partial plan view showing the bed spring and mattress supporting frame mounted upon the side bars of the bedstead. Fig. 2 is an enlarged cross sectional view, indicated by the line II. II. of Fig. 1, showing both side bars of the bedstead, with the bed spring and mattress supporting frame mounted thereon. Fig. 3 is a similar view showing the frame mounted on the ordinary slats of a wooden bedstead, the supporting hangers being thrown back in holding engagement with the cross bars. Figs. 4 and 5 are enlarged detail plan views showing the supporting hanger in extended and retracted positions, respectively.

In the drawings, 2 represents the side bars of the usual well-known metal bedstead, which may be of any suitable construction, but are preferably of angle shape. These bars extend longitudinally along each side of the frame and are preferably removably connected with the corner posts, as will be readily understood.

The mattress or spring supporting frame,

which may be made in one, two or more sections, is composed of side bars 3 and transverse bars 4 connected together in any suitable manner, as indicated at 5, preferably by bending the ends of bars 4 into side contact engagement with the inner faces of bars 3 and riveting them together. This construction of joint is, incidentally, of advantage in providing a double thickness of the side 60 and cross bars at the points where the supporting hangers are located, thus providing a double thickness bearing for the hangers.

The spring frame 6 having the customary springs 7 is usually mounted upon the cross 70 bars 4 providing a support for the mattress, or any other desired spring construction or mattress support may be utilized, without necessarily changing the construction or functions of the invention.

For the purpose of providing a supporting engagement between the frame composed of bars 3 and 4, and the side bars 2, I provide the hangers 8, preferably one for each end portion of the cross bars 4. These 80 hangers are made of flat strip metal of sufficient size and thickness to provide ample strength and rigidity, and are bent into U-shaped form at their outer portions, adapted to fit over and embrace the upper portion of 85 bars 2.

The hanger is so shaped as to provide a right angle joint, as indicated at 9, fitting around underneath the lower edge of side bars 3, and, incidentally, underneath the 90 flanged ends of cross bars 4, as shown in Fig. 2, and is then extended backwardly underneath the side bar 3 and pivotally connected to the lower portion of bar 4 by a rivet or bolt, as indicated at 10.

The metal bar forming the hanger is twisted, as at 11, for one-quarter of a complete revolution, thus providing for side lapping of its inner end portion against the inner side face of bar 4, a washer 12 being 100 preferably employed between the pivoting end of the hanger and the cross bar, whereby to space the body portion of the hanger outwardly somewhat from the face of bar 4. Additional washers 13 may also be used, 105 if desired. As thus constructed, the flat portions of the strip forming the hanger are thus presented to the various engaging surfaces and the inner end of the hanger is thus well adapted to pivotal mounting 110 alongside of bar 4. When extended, as shown in Fig. 2, the device thus presents

ample bearing surfaces for engagement with the side and cross bar members of the mattress supporting frame, and also for good embracing and supporting engagement with the side bars 2 of the bedstead.

When it is desired to use the spring mattress frame on an ordinary bedstead provided with the usual wooden slats 14, supported on the side bars 15, the hanger members are turned backwardly underneath side bars 3 and swung around and pressed upwardly, the curved edge 16 of the hanger strip binding with considerable pressure against the inner face of bar 4, deflecting the hanger outwardly therefrom, as shown in Fig. 5, effecting spring pressure inwardly against bar 4 and resulting binding and holding friction. The metal strip of the hanger having considerable resiliency, this action is facilitated, effecting a considerable degree of binding friction when the hanger is thrown clear up, as in Fig. 3, thereby positively holding it in reversed position and away from contact with any other portion of the structure, avoiding rattling, etc. This spring action is directly facilitated by the use of the outer washer 13, whereby the hinge or pivotal joint is maintained without distortion, the washer also assisting in holding, by spring action, of the hanger against the frame.

The advantages of the invention will be readily appreciated by all those familiar

with this class of devices; it is comparatively simple and cheap in construction, efficient in operation, provides ample strength for the objects in view, and is not liable to get out of order.

Having described our invention, what we claim is:

In a mattress supporting frame, the combination with the end bar and a cross bar connected therewith at right angles, of a hanger having an outer U-shaped portion adapted to engage over a supporting side bar, a middle flat portion adapted to bear simultaneously underneath the end bar and cross bar adjacent to their juncture and providing a support therefor, and an inner portion twisted into alignment with the cross bar and pivoted thereto closely adjacent to its face, the edge of the twisted portion being adapted to spring laterally and bind against the face of the cross bar to effect frictional holding engagement therewith when the hanger is thrown backwardly thereon, substantially as set forth.

In testimony whereof we hereunto affix our signatures in the presence of two witnesses.

ANGELO PROFETO.
HARRY E. GROSS.
